UNITED STATES PATENT OFFICE.

LAURITS KRISTIAN OLESEN BAKKE, OF EMMETSBURG, IOWA.

CARRIER-OPERATING MECHANISM FOR BINDERS.

Application filed January 29, 1921. Serial No. 441,036.

To all whom it may concern:

Be it known that I, LAURITS KRISTIAN OLESEN BAKKE, a citizen of the United States, residing at Emmetsburg, in the county of Palo Alto, State of Iowa, have invented a certain new and useful Carrier-Operating Mechanism for Binders, of which the following is a specification.

The object of my invention is to provide 10 a carrier operating mechanism for binders which is of comparatively simple construction, very durable and comparatively cheap to manufacture.

More particularly my invention relates to 15 an attachment for binders whereby the bundle carrier device of the binder may be operated automatically from power furnished by the binder.

Still another object is to provide suitable 20 mechanism for causing the bundle carrier device to be tripped or swung to discharging position, and returned to normal position; the mechanism being driven from a moving part of the binder.

25 Still another object is to provide means for holding the bundle carrier operating mechanism inoperative during the time the bundle carrier is having bundles discharged from the conveyor thereon.

30 Still another object is to provide a controlling device adapted to be controlled from a distant point from the operating mechanism for throwing the bundle carrier operating mechanism into operative position for swinging the bundle carrier to discharging position and back again.

Still a further object is to provide such 35 a bundle carrier operating mechanism that after a complete operation of the bundle carrier the parts will automatically be thrown out of engagement and held in that position until the controlling device is again actuated.

Still a further object is to provide suitable 40 means for varying the position of the bundle carrier operating mechanism relative to the bundle carrier so that the movement of the bundle carrier may be varied as desired.

50 Still a further object is to provide yielding means for throwing the carrier operating mechanism into engagement with a device driven from the binder so that the carrier operating mechanism may be operated

for moving the bundle carrier; the parts being so arranged that when the controlling device is operated the holding means is released and then the yielding means throws the carrier operating mechanism into engagement and operative position. 55 60

Still another object is to provide a carrier operating mechanism adapted to be operated from a moving part of a binder, the operating mechanism being suitably mounted on the seat beam or pipe of the binder so as not to interfere with the ordinary conveyor mechanism of the binder. The carrier operating mechanism is so provided that its operation may be controlled from a point distant from the ordinary carrier tripping mechanism which is ordinarily provided on a binder. 65 70

Still another object is to provide such an attachment for operating the bundle carrier by power, the attachment being so designed that it will operate in connection with the ordinary control or trip device of the bundle carrier. 75

Still another object is to provide means 80 for operating the bundle carrier of a binder by power supplied from a moving part of the binder; the operating mechanism being so provided that after a complete cycle of operation of the bundle carrier has been performed the operating mechanism will 85 then be automatically disengaged and at the same time will be held out of engagement until a manually operable control device is again operated.

With these and other objects in view my 90 invention consists in the construction, arrangement and combination of the various parts of my device, whereby the objects contemplated are attained, as hereinafter more fully set forth, pointed out in my claims, 95 and illustrated in the accompanying drawings, in which:

Figure 1 is a diagrammatic, perspective view of my carrier operating mechanism attached to a binder, the bundle carrier and control device being shown in connection therewith. 100

Figure 2 is a side elevation of my improved operating mechanism.

Figure 3 is a detail sectional view taken 105 on the line 3—3 of Figure 2.

Figure 4 is a side elevation of my device taken on the opposite side of the device as

that shown in Figure 2 and showing the way power is applied from the binder.

Figure 5 is a rear end view of my device.

Figure 6 is a detail sectional view taken 5 through the holding device for holding the parts inoperative.

Figure 7 is an enlarged detail sectional view taken on the line 7—7 of Figure 6.

Figure 8 is a detail sectional view showing 10 how the power from the binder is reversed.

Figure 9 is a side elevation of my device similar to Figure 2 showing a modified form of driving the device and for controlling the device.

15 Figure 10 is a rear view of my device as shown in Figure 9; and

Figure 11 is an enlarged, detail view taken on the line 11—11 of Figure 9.

In the accompanying drawings I have 20 used the reference numeral 10 to indicate the frame of a binder to which is secured an auxiliary frame 11 which supports the bundle carrier 12. The auxiliary frame 11 is provided with braces 13 which are secured 25 to the binder supporting frame 14.

The parts just described are of the ordinary type found upon practically all makes of binders.

The bundle carrier 12 is composed of fingers 30 15 which have their inner ends fixed to a swinging bar 16. The swinging of the bar 16 causes the fingers to be moved to discharging position and return to their normal position.

35 Fixed to the binder frame 10 is a seat pipe or beam 17 which is provided with a suitable bearing 18. The grain when cut passes upon a conveyor 19 which delivers the grain after it has been bound into a bundle by the binder mechanism (not shown) onto the bundle carrier 12.

A bearing 20 is fixed to the frame 11 and is substantially in alignment with the bearing 18. A bundle carrier rocking shaft 21 45 is journalled in the bearings 18 and 20 and has one of its ends bent substantially at right angles so as to form an arm 22.

Fixed to the rocking shaft 21 adjacent to the bearing 18 is an arm 23. An ordinary 50 foot trip device 24 is mounted on a supporting bar 32 and is capable of swinging movement.

The foot trip 24 is provided with a crank portion 25. The lower end of the foot trip device and the arm 23 are connected together by means of a connecting rod or link 26.

55 The swinging bar 16 of the carrier 12 is connected to the arm 22 of the rocking shaft 21 by means of a link 27.

From the construction of the parts just described it will be seen that the moving of the foot trip device in the direction indicated by the arrow 28 will cause the connecting rod 26 to move in the direction of

the arrow 29, which in turn will cause the link to move in the direction indicated by the arrow 30.

The bundle carrier 12 will then move in the direction indicated by the arrow 31 75 which is the normal movement; that is a rearward and downward movement of the bundle carrier so that any bundles of grain upon the carrier will be slid off onto the ground.

75 My device is adapted to operate in connection with the bundle carrier and the control rods for operating the same. My device consists of a beam or supporting bar 32 which rests upon the seat pipe or beam 17 80 and is held thereon by means of a two-part bearing or gripping device 33.

One of the parts of the bearing 33 is fixed to the beam or support 32 while the other part extends part way around the seat beam 17. The two parts of the bearing 33 are held together by bolts 34.

The entire mechanism of my device which operates the bundle carrier is mounted upon the beam 32.

90 Substantially near the rear end of the beam 32 I provide a casting 35 which is provided with a pair of bearings 36 and 37. A stub shaft 38 is provided in the bearing 36.

A sprocket wheel 39 and a gear 40 are 95 loosely mounted on the shaft 38. The sprocket 39 and gear 40 are held together by means of bolts 41.

In order to drive the gear 40 from a moving part of the binder I mount a sprocket 100 42 on the conveyor shaft 43. A chain 44 connects the sprocket 42 with the sprocket 39 for driving the latter.

A casting 45 is fixed to the beam 32 and is provided with bearing portions 46 and 47. 105 The bearing portion 46 is in alignment with the bearing 37 of the casting 35 and a shaft 48 is journalled in the bearings 37 and 46.

The rear end of the shaft 48 extends beyond the bearing 37 and has fixed thereto 110 a gear 49 in mesh with the gear 40.

From the construction of the parts just described it will be seen that the shaft 48 is driven in the opposite direction from the conveyor shaft 43. The reverse of the direction of the shaft 48 is caused by the use of the stub shaft 38 and the gear 40. The conveyor shaft travels in the direction indicated by the arrow 50 while the shaft 48 travels in the direction indicated by the arrow 51.

115 Rotatably mounted in the bearing 47 is a shaft 52 to which is fixed an incomplete crown gear 53. The crown gear 53 is provided with a flat or incomplete portion 54. 120 The incomplete portion 54 has no teeth thereon, as is illustrated in Figure 3 of the drawings.

The gear 53 is provided with a web or disc portion 55 which is provided with slots 56,

the purpose of the slots 56 being hereafter more fully set forth.

The shaft 48 is provided with a gear 57 which is designed to mesh with the crown gear 53, and which normally rests against the incomplete portion 54 of the gear 53, as shown in Figure 3 of the drawings.

When the teeth of the crown gear 53 mesh with the gear 57 then the crown gear 53 is rotated.

A pitman 58 is pivoted at one end to a bolt 59 which is received in one of the slots 56. The free end of the pitman 58 is pivoted to a bolt 60 which is fixed to the upper end of the arm 24.

From the construction of the parts just described it will be seen that when the gear 57 which is always being driven from the conveyor shaft 43 is permitted to engage or mesh with the crown gear 53 that the rotation of the crown gear 53 will cause the movement of the pitman.

The movement of the pitman 58 causes the arm 24 to be swung upon its crank portion 25, which in turn causes the rearward movement of the short arm 23 on the rocking shaft 21; this operation imparts movement to the bundle carrier 12.

The parts are so arranged that when the bundle carrier 12 is in its normal position the gear 57 rotates adjacent to the incomplete portion 54 of the gear 53.

It will be understood that it is necessary to provide some means for first moving the gear 53 to position where it will mesh with the gear 57.

In order to provide for such movement I employ a spring 61 which is wound around the bolt 60 and has one end engaged with the pitman 58 and the other end with the arm 24. The spring 61 normally tends to move the gear 53 to the position shown in dotted lines in Figure 2 of the drawings.

It is not desirable to cause the bundle carrier to operate at regular spaced intervals so it is necessary to provide some means for preventing the spring 61 from causing the gears 53 and 57 to mesh.

In order to hold the gear 53 out of engagement with the gear 57 I provide a pivoted pawl 62 pivoted on the bolt 63.

The pawl 62 is composed of a pair of similar spaced members which are slightly spaced apart, and are provided with a filler block 64 near their upper ends.

The pawl 62 is pivoted in a frame 65 which is composed of a pair of similar shaped members having a spacer 66 placed therebetween near their upper ends, and a screw 67 is extended through the frame 65 and the spacer 66, and received into a portion of the casting 35.

The frame 65 is also fixed to the casting 35 by means of a small bolt 68.

The two members of the pawl 62 are pro-

vided with openings which receive a short pin 69 which has a roller 70 thereon. The purpose of the roller 70 will be hereafter more fully set forth.

Bolted to the lower end of the two members of the pawl 62 and received therebetween is a lever or arm 71 which is extended on each side of the pawl 62, as shown in Figure 2 of the drawings.

The rear end of the arm 71 has fastened thereto a spring 72 which is fixed to a lug 73 on the frame 65. The spring 72 normally holds the upper end of the pawl 62 in its forward position.

A lug 74 is formed on the pawl 62 on one side of the frame 65 and is designed to engage the frame 65 for limiting the amount of forward movement of the pawl 62.

A similar lug 75 is formed on the pawl 62 on the opposite side from the lug 74. The lug 75 limits the amount of rearward movement of the pawl 62.

Fixed to the disc 55 of the gear 53 is a locking or engaging member 76. One end of the engaging member 76 projects out beyond the periphery of the disc 55. The engaging member 76 is in alignment with the space between the two members of the pawl 62.

When the disc 55 is rotated the engaging member 76 first strikes the roller 70; as the disc continues to rotate the pawl 62 is moved rearward against the action of the spring 72 until the engaging member strikes against the filler block 64.

When in this position the pawl 62 locks the gear 53 against any further movement. When in this position the gear 57 rests adjacent to the incomplete portion of the gear 53.

The pawl 62 counteracts the normal movement of the spring 61 which would normally tend to throw the gear 53 into engagement with the gear 57.

It will be seen that I have provided a holding device for automatically engaging the member 76 for preventing any further movement or operation of the mechanism which operates the bundle carrier.

Fixed to the forward end of the beam 32 and extending upwardly therefrom is an angle iron frame 77 which has pivoted thereto at its upper end a disc 78. The disc 78 is provided with a notch 79 in its edge, as illustrated in Figure 2 of the drawings.

One side of the angle iron frame 77 extends part way into the notch 79 so that the pivotal movement of the disc 78 in either direction will be limited.

A brace 80 has one end fixed to the angle iron frame 77 and its other end to the seat support 81 of the binder.

A bell crank lever 82 is pivoted at 83 on the beam 32, one end of the bell crank lever 82 being connected to one end of the arm 71

by means of a link or rod 84. The opposite end of the bell crank lever 82 has a rod 85 pivoted thereto and extends upwardly adjacent to one side of the angle iron frame 57 and has its upper end pivotally fixed in the disc 78.

A rod 86 is pivoted in the disc 78 and extends forwardly therefrom.

The parts just described are what may be 10 termed the controlling device, which controls the operating mechanism for the bundle carrier.

The rod 86 may extend forward to a distant point or may have a wire or rope fixed 15 thereto so that the disc 78 may be slightly turned or moved on its pivot from the driver's seat of a tractor.

The pulling of the rod 86 forward will cause the bell crank lever to be swung on 20 its pivot which will move the rod or link 84 in the direction indicated by the arrow 87.

The arm 71 will then be swung on its pivot 63 to a position which will cause the 25 pawl 62 to disengage the member 76 on the disc 55.

As soon as the member 76 has been freed from the locking pawl 62 the spring 61 will cause the gear 53 to be moved to position 30 where it will engage the gear 57.

When the gears 53 and 57 are in engagement the power from the binder will cause the tripping mechanism to operate the bundle carrier to move it to position where the 35 bundles will be discharged therefrom, and then returned.

The engaging member 76 and the locking pawl 62 will engage as soon as one complete 40 cycle of operation of the bundle carrier has been performed.

The operating mechanism then remains 45 inoperative until the operator again pulls the rod 86 which causes the pawl 62 to disengage from the member 76 and again permits one complete cycle of operation of the bundle carrier.

The slots 56 are provided so that the pitman may be adjusted relative to the position of the various parts of the device.

When the pitman is adjusted it causes the 50 normal position of the bundle carrier and the controlling rods 21 and 27 to be slightly changed so that with each operation of the carrier operating mechanism the carrier will be moved to discharging position and returned.

The amount of movement of the carrier may be varied by changing the position of the pitman 58 relative to the remainder of the parts of the operating mechanism. It 60 will be understood that by shifting the position of the pitman, it will cause the original or starting position of the bundle carrier to be changed so that the actual amount of movement of the bundle carrier may be 65 varied.

It will be seen that with my device the power from the binder is used for operating the bundle carrier and that I am able to control the operation of the bundle carrier from a point distant from the binder. 70

I am able to operate my device from the tractor seat without the use of anyone on the binder.

My device furnishes a positive means for operating the bundle carrier and no effort 75 on the part of the operator is necessary save for the tripping of the pawl 62, or the tripping of a foot release which may be located near the binder seat.

My device may be made as an attachment 80 to be placed on the ordinary binders, or may be originally installed when the binder is manufactured.

In Figures 9, 10 and 11 of my drawings I 85 have shown a slightly modified form of driving mechanism and mechanism for controlling the operation of my device.

The conveyor shaft 43 as shown in Figure 9 is provided with a pulley wheel 88. The shaft 48 which is mounted in the bearings 46 and 37 is provided on its outer end with a pulley wheel 89 which is substantially in alignment with the pulley wheel 88. 90

A belt 91 of any suitable material is placed over the pulley wheels 88 and 89 and 95 is crossed so as to operate the shaft 48 in the direction indicated by the arrow 51.

When the shaft 48 is driven direct from a pulley it is not necessary to use the stub shaft 38 or the gear 40. I have found that 100 by using a belt I can drive the shaft 48 direct, since a belt can be crossed to any desired direction.

It will also be understood that when a chain is used for driving my device it may 105 be connected to some moving part of the binder which is travelling in the proper direction and it will then not be necessary to use the intermediate gear 40 for reversing the direction.

There are a great many makes of binders and it is necessary to provide for some slight change so as to properly install my attachment to the various makes of binders. 110

The bracket 35 as shown in Figure 11 is 115 provided with only one bearing which is 37 in which is mounted the shaft 48.

In this form of device the control mechanism which operates the pawl device is carried below the seat beam and extended forwardly to a position adjacent to the driver's seat of a tractor. 120

When the control device is carried below the seat beam a link 92 is secured to the forward end of the arm 71 instead of the 125 link 84. A lever 93 which lies in a horizontal plane is suitably supported from the binder frame.

The forward end of the link 92 is secured to the lever 93. A cord 94 is fastened to 130

the opposite end of the lever 93 and extends forwardly to the driver's seat of the tractor whereby the cord may be drawn for tripping the pawl which operates my device.

5 By the use of the lever 93 I am able to lead the cord forwardly so that it will not interfere with the cutting mechanism of the binder or the travel of the grain which has been cut.

0 The cord will pass free of the reel of the binder and will not be interfered with by any of the mechanism of the binder.

It will be seen that by this method of driving my device I have eliminated the 15 use of expensive gears and have to a certain extent eliminated part of the bearings and yet have provided a very simple and efficient device.

It will be further understood that I have 20 shown two different forms of mechanism for driving the device, but it is understood that I intend to cover by my claims various methods which may be used in driving the device which may be reasonably included 25 within the scope of my claims.

It will be further understood that slight changes will have to be made for adjusting and regulating the positioning of my device on a binder so that it will operate effectively 30 on various makes of binders.

Some changes may be made in the construction and arrangement of the parts of my machine without departing from the real spirit and purpose of my invention, and 35 it is my intention to cover by my claims, any modified forms of structure or use of mechanical equivalents, which may be reasonably included within their scope.

I claim as my invention:

40 1. The combination of a binder having a bundle carrier capable of moving from carrying to discharging position and back, with a carrier operating mechanism arranged to be operated from a moving part 45 of the binder, means for moving said carrier operating mechanism to position for such operation, and means for varying the position of the carrier operating mechanism relative to the bundle carrier whereby the 50 amount of movement of the bundle carrier may be varied.

2. The combination of a binder having a bundle carrier capable of moving from carrying to discharging position and back, 55 with a carrier operating mechanism arranged to be operated from a moving part of the binder, means for moving said carrier operating mechanism to position for such operation, means for varying the position 60 of the carrier operating mechanism relative to the bundle carrier whereby the amount of movement of the bundle carrier

may be varied, and means for automatically holding said carrier operating mechanism in inoperative position.

3. The combination of a binder having a bundle carrier capable of moving from carrying to discharging position and back, with a carrier operating mechanism arranged to be operated from a moving part 70 of the binder, means for moving said carrier operating mechanism to position for such operation, means for varying the position of the carrier operating mechanism relative to the bundle carrier whereby the 75 amount of movement of the bundle carrier may be varied, and means for automatically holding and throwing said carrier operating mechanism into operative position.

4. In combination with a binder having 80 a bundle carrier thereon, a tripping mechanism operatively connected with the bundle carrier, said tripping mechanism including a shaft driven from the binder, a gear on said shaft, an incomplete gear connected 85 with the tripping mechanism and adapted when in mesh with said first gear to impart movement to said tripping mechanism for operating the bundle carrier and means for varying the position of the tripping mechanism relative to the bundle carrier for varying the amount of movement of the 90 carrier.

5. In combination with a binder having 95 a bundle carrier thereon, a tripping mechanism operatively connected with the bundle carrier, said tripping mechanism including a shaft driven from the binder, a gear on said shaft, an incomplete gear connected with the tripping mechanism and 100 adapted when in mesh with said first gear to impart movement to said tripping mechanism for operating the bundle carrier, means for varying the position of the tripping mechanism relative to the bundle carrier, and a manually controlled device for 105 permitting engagement of said first and second gear.

6. In combination with a binder having a bundle carrier and operating mechanism 110 therefor, a tripping mechanism for actuating said operating mechanism, said tripping mechanism including an incomplete gear fixed to said operating mechanism, a driven gear capable of meshing with said 115 incomplete gear, driven from a moving part of the binder, means for holding said gears out of mesh with each other, and spring means for throwing said incomplete gear into mesh with said gear when the holding 120 means is released.

Des. Moines, Iowa, January 19, 1921.

LARITS KRISTIAN OLESEN BAKKE.
